PLAYER ACTION COMPANY, OF DEEP RIVER, CONNECTICUT, A CORPORATION OF
CONNECTICUT.

PLAYER-PIANO.

1,329,702.

Specification of Letters Patent. Patented Feb. 3, 1920.

Application filed May 8, 1918. Serial No. 233,217.

To all whom it may concern:

Be it known that I, STANLEY L. FISHER, a subject of the King of Great Britain, residing in Chester, county of Middlesex, 5 State of Connecticut, have invented certain new and useful Improvements in Player-Pianos, of which the following is a full, clear, and exact description.

This invention relates to player pianos, 10 and it has more particular reference to pneumatically actuated pianos of the upright type, wherein a so-called "upper action" or chest with its appurtenant valve mechanism and pneumatics for operating the respective units of the piano action proper extends across the front of the piano in the case thereof above the key-board and in front of the piano action, each unit of the 15 player action being properly connected with 20 and adapted to operate the corresponding unit of the piano action. Each piano action unit ordinarily comprises a hammer for striking the string, a pivoted wippen or jack beam, and a hammer jack mounted on the 25 wippen in the customary manner, the wippen being operated to actuate the hammer by a connection with the corresponding player action unit for pneumatic playing, and said wippen being connected with the 30 corresponding key of the piano for playing by hand.

One of the primary objects of my invention is the provision of an improved and simplified player action of the general type 35 set forth, which has the advantages of compactness, efficiency of operation, ready accessibility for inspection and adjustment, and low cost.

More specifically, the object of my invention is to provide an improved form of connection between each striker pneumatic and the corresponding unit of the piano action, by which the number of parts is cut down, while, at the same time, provision is made 45 for an easy but nice adjustment, whereby the hammers may be caused to strike the strings properly and uniformly.

To these and other ends, the invention consists in the novel features and combinations of parts to be hereinafter described and claimed.

In the accompanying drawings:

Figure 1 is a diagrammatic vertical transverse section through the upper portion of 55 a player piano embodying my improvements,

showing the main parts of one of the piano action units, and the wind chest, valve mechanism and striker pneumatics of the player action;

Fig. 2 is a top plan view of certain parts 60 shown in Fig. 1, partly in section on line 2-2 of Fig. 1; and

Fig. 3 is a section on line 3-3 of Fig. 1. In the practice of my invention, the piano action A can be for the most part of usual 65 type, although various changes may be made in this respect. In the embodiment illustrated, I have shown the ordinary form of piano action unit, comprising a hammer 10 for striking the string 11, pivoted at 12 to 70 the rail 13, from which is pivotally supported at 14 the customary wippen 15, carrying the usual pivoted hammer jack 16 and other parts which I have not considered it necessary to illustrate. Pivoted to the 75 wippen 15 near the outer free end of the same is the customary sticker or abstract 17. The pivot between the abstract and wippen is shown at 18. Extending across the 80 front of the piano in front of the piano action above the key board (not shown) is a pneumatic player action designated generally by B. This pneumatic action B comprises a chest work C, beneath which are carried a plurality of striker pneumatics 19 85 preferably arranged in two different tiers, as shown. These pneumatics project rearwardly from the chest work C toward the piano action units, there being one pneumatic for each of said units. The pneumatics of the two tiers are arranged in staggered relation. The pneumatics of the upper tier extend at their rear extremities into close proximity to the forward ends of the wippens of the piano action, being arranged at approximately the same level as said wippens, while the pneumatics of the other tier are slightly below the wippens. Preferably, the pneumatics of both tiers are inclined slightly in an upward and rearward 95 direction, as shown. The particular construction of the chest work C is immaterial to the present invention, but it may be said that each of the striker pneumatics 19 is controlled by a 100 valve 19^a and that each valve 19^a is controlled in turn by a diaphragm 19^b, which, in turn, is controlled in the customary manner from the usual tracker bar D. The pneumatics 19, whose moveable leaves are 110

lowermost, are collapsed by the admission of air to the action through the perforations in the music sheet and the holes in the tracker bar in the customary manner. As 5 the pneumatics collapse, their lower movable parts or leaves are raised and this movement is transmitted to the corresponding wippens 15 of the piano action, in such a manner that the strings are properly struck by 10 the hammers. For this purpose, each of the wippens of the piano action is adapted to be actuated by a rigid striker on the corresponding pneumatic. In the form shown, each of the upper pneumatics has a small, 15 rigid striker constituted by a cleat or extension 20 rigidly secured by a screw 21 to the under surface of the movable leaf of the pneumatic at the rear of said leaf. A part of the cleat extends rearwardly beyond the 20 leaf and under a button 22 carried by the wippen at the forward end thereof. The button 22 has a layer of felt 22^a on its lower surface, adapted to be struck by the corresponding rigid striker extension or projection 20. The normal position of the parts is shown in Fig. 1, from which it will be manifest that as the upper pneumatics 19 are collapsed, the buttons 22 will be raised, thereby carrying upward the front parts 30 of the respective wippens and moving them about their pivots 14 so as to actuate the corresponding hammers. The buttons 22 appurtenant to the pneumatics of the lower tier are arranged in line with those appurtenant to the upper pneumatics, all of 35 the buttons of the whole piano action being substantially in line with each other, and the lower pneumatics are provided with rigid strikers which extend up into co-operation with the corresponding buttons. The rigid strikers of the lower pneumatics are formed by cleats 23 secured to the lower leaves of said pneumatics by screws 21 in substantially the same relation as the cleats 40 20, but the cleats 23 are provided with rigid upward extensions 23^a located adjacent the rear ends of the lower pneumatics and presenting rigid finger-like members which extend at their upper ends into the spaces 45 between the cleats or strikers 20 with which they alternate. The strikers of both tiers of pneumatics are preferably made of wood, and their upper striking surfaces, co-operating 50 with the buttons 22, are preferably curved, so as to make the most advantageous striking contact with the buttons. The buttons 22 are vertically adjustable, inasmuch as they are provided with threaded stems or shanks 24 engaging 55 threaded sockets passing through the front ends of the respective wippens in a substantially vertical direction. At their upper ends, the threaded shanks of the buttons are provided with manipulating heads 25, which 60 enable them to be screwed up and down, 65

i. e., toward or away from the coöperating rigid strikers 20 or 23. In this manner, a very nice adjustment of the player action can be obtained after the same has been installed in the piano case, and all lost motion between the pneumatics and the corresponding wippens can be readily taken up, so that a full actuation of the piano action unit by the corresponding player action unit will be insured. On the other hand, in 70 order to prevent an upward movement of the wippen beyond the extent required, a suitable stop mechanism is provided, which coöperates with the forward end of the wippens. Preferably, the stop mechanism 75 includes a rail 26 extending across the upper faces of the upper pneumatics at the rear of said pneumatics and disposed lengthwise of the piano, said rail being provided with a plurality of independently adjustable stop 80 buttons 27. The rail 26 may be supported in any suitable manner on the player action. The buttons 27 are preferably similar to the buttons 22, having threaded shanks 28 engaging screw threaded openings in the 85 stop rail 26 and provided at their upper ends with manipulating heads 29. The rear part of the stop rail projects beyond the upper pneumatics so as to partially overhang the same, and the stop buttons 27 are 90 supported by the overhanging portion of the rail, with the buttons below the rail close to the rear ends of the pneumatics, and the manipulating heads 29 above the rail, where they are readily accessible from above. 95 Preferably, the front end of each wippen is 100 beveled or chamfered, as shown at 30, so as to present an upwardly and rearwardly inclined stop surface which contacts flatwise with the felt layer 27^a of the corresponding stop button when the wippen is raised. The arrangement is such that when the wippen is arrested at about the usual upper limit of its movement, the stop surface 30 thereon is substantially parallel to and in contact 105 with the lower surface of the stop button, whereby a cushioned but very effective stop is provided. When one of the pneumatics is collapsed, the corresponding wippen is raised until its beveled surface engages the 110 under surface of the corresponding stop button, which should previously be adjusted to the proper height by manipulation 115 of its threaded shank. 120 It will be observed that the contact buttons on the wippens and the stop buttons on the stop rail are arranged very close together and both series are accessible for adjustment from above. The stop buttons and the contact buttons may, therefore, be readily regulated from closely adjacent points, the two series being parallel to each other and compactly arranged for the greatest accessibility. It will be observed that, while the stop buttons are normally located above the 125 130

- contact buttons, the shanks of the buttons of the two series are approximately parallel to each other, the threaded shanks 24 of the contact buttons 22 passing through approximately vertical threaded sockets in the respective wippens, which sockets are located at substantially the rear boundaries or margins of the respective stop surfaces 30 of the wippens.
- 10 The arrangement described is extremely compact, takes up very little room in the piano case, comprises very few parts, and yet provides a very nice adjustment. A minimum number of parts is interposed between each pneumatic and the corresponding piano action unit, and yet the provision for taking care of lost motion between the pneumatic, the striker and the wippen, and for limiting the swing or play of the wippen, is simple, efficient and generally satisfactory.

In installing the player action, it is merely necessary to locate the chest work properly with respect to the piano action units, after which the adjustment of the various contact buttons and stop buttons is a very easy matter. These buttons are very readily accessible from above the chest work as long as the upper front panel of the piano case is removed.

30 Various changes may be made in the details of the construction without departing from the scope of my invention as defined in the claims.

I do not claim herein the chest structure and valve mechanism, as the same is claimed in my application Serial No. 230,417; nor do I claim broadly herein striker members projecting rigidly from the movable leaves of pneumatics of different tiers and having striking surfaces located in substantially a single line or series extending across the piano for contacting with the piano action units and thereby actuating the same, nor the provision of stop means carried by and forming an integral part of the pneumatic player action for limiting the movement of the piano action units, nor other features broadly claimed in said application.

- What I claim is:
- 50 1. In a player piano, piano action units including wippens and stickers, a wind chest in front of the same, tiers of pneumatics connected to said wind chest and extending rearwardly therefrom, means for collapsing said pneumatics, and striker members rigid with the movable leaves of said pneumatics and projecting under the front ends of said wippens for lifting the same directly independently of said stickers.
- 60 2. In a player piano, a piano action including a plurality of wippens, a wind chest in front of the same, upper and lower staggered tiers of pneumatics connected to said wind chest and extending rearwardly therefrom, said pneumatics having their movable

leaves lowermost, and striker members rigid with the movable leaves of said pneumatics and arranged to contact with front end portions of said wippens to lift the same.

3. In a player piano, piano action units including wippens, a pneumatic player action in front of the same having staggered tiers of pneumatics extending rearwardly toward said units and having their movable leaves lowermost, the upper tier of pneumatics being substantially at the same level as said wippens, striker members on the movable leaves of the pneumatics of the upper tier extending under the front ends of certain wippens for lifting the same directly, and striker members carried wholly by and projecting rigidly upward from the movable leaves of pneumatics of a lower tier into spaces between said first named striker members and beneath other wippens for lifting the same directly.

4. In a player piano, piano action units including wippens, a pneumatic player action in front of the same including a wind chest and tiers of pneumatics connected to said chest at the lower part thereof and inclined rearwardly and upwardly toward said piano action units, said pneumatics having their movable leaves lowermost, and the upper tier of pneumatics being substantially at the same level as said wippens, and striker members carried wholly by and having fixed relation to the movable leaves of the pneumatics of said tiers and projecting under the front ends of said wippens in close proximity thereto in order to act on and lift the same directly.

5. In a player piano, piano action units including wippens, a pneumatic player action structure in front of the same having staggered tiers of pneumatics extending rearwardly toward said units and having their movable leaves lowermost, one tier of pneumatics being substantially at the same level as said wippens, and striker members having a fixed relation to the movable leaves of the pneumatics of said tiers and projecting under the front ends of said wippens in close proximity thereto in order to act on and lift the same directly.

6. In a player piano, a plurality of piano action units each including a wippen, a wind chest in front of said units, pneumatics operatively connected with said chest and extending rearwardly therefrom, said pneumatics arranged in different tiers in staggered relation, rigid strikers on the movable leaves of said pneumatics at the rear ends thereof, and adjustable buttons carried by the wippens and overlying said strikers so as to be lifted thereby when the pneumatics are collapsed, whereby said piano action units are actuated, said buttons all being located in a single series and the upper ends of the strikers of the upper and

lower pneumatics lying in substantially a single plane.

7. In a player piano, a plurality of piano action units including wippens, a wind chest 5 in front of the same, pneumatics projecting rearwardly from said chest and having their movable leaves lowermost, said pneumatics arranged in different tiers, projections rigid with the movable leaves of said pneumatics 10 at the ends thereof, the projections of both tiers of pneumatics having their upper ends located in substantially a single plane, and adjustable contact buttons in said plane engageable by said projections and carried 15 by the wippens above the latter.

8. In a player piano, a piano action unit including a wippen, an adjustable contact button carried by the wippen, a pneumatic player action including a rearwardly extending 20 pneumatic in front of the piano action unit, having a movable lower leaf, a rigid striker member on said movable leaf underlying said contact button, and an adjustable stop button forming a part of the 25 pneumatic action structure and positioned to be engaged by the forward end of the wippen and to limit the upward throw thereof.

9. In a player piano, a plurality of piano 30 action units including wippens, said wippens provided at the upper forward parts thereof with stop surfaces, a pneumatic player action including pneumatics having means for engaging said piano action units, 35 a stop rail secured to and forming an integral part of said player action and extending across the piano action, and upwardly adjustable buttons on said stop rail for engagement by the corresponding stop surfaces 40 of the wippens to thereby limit the upward throw of said wippens.

10. In a player piano, a plurality of piano action units including wippens, said wippens provided at the upper forward parts 45 thereof with stop surfaces, contact buttons beneath the forward ends of said wippens having threaded shanks passing through the respective wippens at the rear of said stop surfaces, a pneumatic player action including 50 pneumatics having means for engaging said contact buttons, a stop rail secured to and forming part of said player action and extending across the tops of said pneumatics adjacent the rear edges thereof and upwardly adjustable buttons on said stop rail 55 in front of and above said contact buttons

for engagement by the corresponding stop surfaces of the wippens to thereby limit the upward throw of said wippens.

11. In a player piano, a plurality of piano action units, including wippens, said wippens provided at the upper forward parts thereof with stop surfaces, contact buttons beneath the forward ends of said wippens having threaded shanks passing through the 60 respective wippens at the rear of said stop surfaces, a player action including pneumatics having means for engaging said contact buttons, a stop rail secured to said player action adjacent the rear ends of said pneumatics, and upwardly adjustable buttons on 65 said stop rail in front of and above said contact buttons for engagement by the corresponding stop surfaces of the wippens to thereby limit the upward throw of said wippens, the stop surfaces of said wippens being upwardly and rearwardly inclined, and said stop buttons being disposed at the rear of said pneumatics and having threaded shanks 70 engaging a portion of said stop rail projecting rearwardly beyond the rear upper edges of said pneumatics.

12. In a player piano, a plurality of piano action wippens, a wind chest, pneumatics arranged in tiers and operatively connected 85 to said wind chest, strikers rigid with the movable leaves of said pneumatics, the upper ends of said strikers lying in substantially a single plane, for contact with said wippens. 90

13. In a player piano, a piano action including wippens, a player action, and means attached to and forming part of said player action and extending across said wippens to limit the operation of said wippens. 95

14. In a player piano, a piano action including wippens, a player action including a wind chest having rearwardly extending pneumatics arranged in tiers, strikers rigid with the movable leaves of said pneumatics 100 and having their upper surfaces lying in substantially a single plane for contact with said wippens, and a stop rail forming an integral part of said player action and extending across the same above and 105 slightly to the rear of the pneumatics of the upper tier for engaging and limiting the swinging movement of said wippens.

In witness whereof, I have hereunto set my hand on the 2nd day of May, 1918.

STANLEY L. FISHER.
